UNITED STATES PATENT OFFICE

97,090

DESIGN FOR AN AIRPLANE

Steffen P. Nemeth, Chicago, Ill.

Application June 24, 1935, Serial No. 57,388

Term of patent 14 years

To all whom it may concern:

Be it known that I, Steffen P. Nemeth, a citizen of the United States, residing at Chicago, in the county of Cook and State of Illinois, have invented a new, original, and ornamental Design for an Airplane, of which the following is a specification, reference is had to the accompanying drawing, forming a part of this specification.

Figure 1 is a front view of an airplane embodying my design;

Figure 2 is a side view of the same; and
Figure 3 is a top view of the same.

The dominant feature of my design resides in the wing portion.

I claim:

The ornamental design for an airplane substantially as shown and described.

In testimony whereof I affix my signature.

STEFFEN P. NEMETH.
